UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,177,020.

Specification of Letters Patent. Patented Mar. 28, 1916.

Application filed November 21, 1913. Serial No. 802,206.

To all whom it may concern:

Be it known that I, CORNELIUS B. CORCORAN, a citizen of the United States, residing in the borough of Bronx, in the county of 5 New York, city and State of New York, have invented certain new and useful Improvements in Type-Writing Machines, of which the following is a specification.

This invention relates to typewriting machines, and more particularly to the stop which arrests the type-bars when near the platen, to cause them to spring against the platen, as shown in the patent to Manning No. 612,858, dated October 25, 1898.

15 My object is to overcome certain difficulties experienced with the stop, which was heretofore formed integral with the type-bar segment, and necessitated adjusting the type-bars in the individual machine 20 for which they were to be used.

With my improved form of stop, which is separate from the type-bar segments, the type-bars may be adjusted on a master machine, and then be placed in individual machines, in each of which the stop may be 25 adjusted to regulate the impression of the types upon the platen. The invention also has other advantages. For the adjustment of this stop, I have provided it with a series of cams which rest in seats or 30 depressions in an adjusting bar. By shifting the latter, the cams may be forced gradually out of their seats, or be permitted to move farther into the same, to bring the type-bar stop into a position where it will arrest 35 the type-bar earlier or later. This adjustment of the stop may also be utilized to quickly regulate the type impressions, when a large number of copies are to be made 40 upon a machine which is normally used for but one or two copies. By setting the said stop back, the types are permitted to strike harder against the platen.

Other objects and advantages will herein- 45 after appear.

In the accompanying drawings, Figure 1 is a front plan view of my invention as applied to the segment of an "Underwood" type of machine, with a type-bar swung 50 against the platen. Fig. 2 is a side elevation, partly sectional, to illustrate the manner in which the type-bar is arrested by the stop, and the type sprung against the platen. Fig. 3 is an enlarged sectional view of the 55 segment, showing a method of fastening the

stop and slide bar in position. Fig. 4 shows the arrangement of the cams on the rear of the stop. Fig. 5 shows the cam seats in the slide bar. Fig. 6 is a detail view, showing the method of adjusting the stop by forcing the cams out of their seats.

In the usual form of an Underwood machine, to which my present invention is shown applied, key levers 1 rock bell cranks 2, which swing bars 3 on fulcrums 4, to 65 strike the types 5 on the outer end of said bars against a platen 6.

A device 7 is arranged to arrest the type-bars 3 just before the type touches the platen. The type springs against the platen 70 and makes its impression.

To regulate the impression of the types, I have provided an adjustment for the stop. The stop 7 is formed independently of the type-bar segment 8, and preferably comprises a stop portion 9, a body portion 10 and cams 11, which rest on seats 12 in an adjusting slide bar 13. This stop is of a segmental form and is fastened to the face of the type-bar segment 8 with screws 14 75 passing through holes in the said stop and slots 15 in the slide bar, to permit the latter to be shifted in the direction of its length while the stop 7 is only movable toward and from the segment, being held against movement in other directions by the screws 14. 80

When the device is to be regulated to permit the types to make heavier impressions, the screws 14 are loosened, and the slide bar 13 is shifted from the Fig. 1 position to the 90 left. This may be done by tapping on the projection 16. This causes the cam seats to be shifted beneath the cams 11, so that when the screws 14 are again tightened, the stop 7 will be drawn closer to the type-bar seg- 95 ment 8, because the said cams settle lower in their seats, and permit the bars 3 to come closer to the platen before being arrested by the stop.

If the slide bar is shifted in the opposite 100 direction, the stop 7 is moved out, and the type-bars are arrested earlier and the type impressions are made lighter.

It will be noted that by my construction the adjustment of the slide bar 13 is always 105 effected in such a manner as to move the stop or body portion 10 in planes parallel to itself. That is, there is no tilting of the bar against which the type strike. The proper position having once been deter- 110

mined, the adjustment to determine the character of the impact must necessarily always be true. In other words, the stop portion 9 will never wiggle or become askew.

5. Variations may be resorted to within the scope of the invention, and portions of the improvements may be used without others.

Having thus described my invention, I claim:

10. 1. In combination with a typewriting machine segment, a plurality of type-bars pivoted in the segment, means for swinging any of said type-bars independently against a platen, a stop arranged on said segment to arrest said type-bars at a certain point of their movement, to cause the type carried thereon to spring against the platen, a series of cams on said stop and means co-operating with said cams, by means of which 15 the latter may be adjusted to arrest the type-bars sooner or later in their movement against the platen.

2. In combination with a typewriting machine segment, a platen, a plurality of type-bars pivoted in the segment, means for swinging any of said type-bars independently toward the platen, a stop arranged on said segment to arrest said type-bars at a certain point of their movement, to cause 25 the type carried thereon to spring against the platen, a series of cams on said stop, a bar, and seats for said cams provided in said bar which may be shifted to gradually force 30 said cams out of said seats or to allow them 35 to sink deeper into the latter, thereby causing the stop to arrest the type bars sooner or later in their swinging movement toward the platen.

3. In a typewriting machine, the combination 40 of a platen, swinging type bars and a stop for said type-bars, and a bar for said stop the said bar and said stop provided with co-operating inclined surfaces to enable adjustment of said stop with reference 45 to the bar to be effected, and means for holding said parts adjusted.

4. In combination with a typewriting machine segment, a platen, a plurality of type-bars pivoted in the segment, means for 50 swinging any of said type-bars independently toward the platen, an adjusting bar, a stop provided with cams seated in depressions in said bar, means for shifting said adjusting bar to adjust said stop and cause 55 it to arrest the type-bars sooner or later in their swinging movement toward the platen, to make a light or heavy impression of the type carried on said type-bars, and means for securing or locking said stop and bar in 60 position on said segment when adjusted.

5. In a typewriting machine, the combination 65 with a type-bar segment, of a set of type-bars pivotally mounted thereon with their pivots arranged in an arc, the type-bars mounted to swing to a common print-

ing center, a two part arc-shaped stop mounted on the segment concentrically with said first-mentioned arc in position to intercept each of the type-bars as it nears the printing point and permit the free end of the type-bars to spring to printing position, a sliding bar, and co-operating means on said bar and stop whereby when the bar is slid the stop is adjusted.

6. The combination with a support, of 75 type-bars mounted to swing thereon to a common printing center, a stop mounted on the support and extending transversely of the type-bars in position to arrest the latter as they near the printing point, and an adjusting device interposed between the stop and its support and comprising cam means for adjusting the stop relatively to its support to thereby vary the point at which the type-bars are arrested.

7. The combination with type-bars arranged to swing to a common printing center, of a support on which the type-bars are mounted, a stop extending transversely of the type-bars in position to arrest the type-bars as they near the printing position, an adjusting slide interposed between the stop and said support and provided with cams for moving the stop to vary the point at which the type-bars are arrested, and means 95 for holding said slide in adjusted position.

8. The combination with a type-bar segment, of a stop mounted thereon, an adjusting slide interposed between the stop and segment, said slide and stop having co-operating cam faces for adjusting the position of the stop relative to the segment when the slide is moved, and means for locking the stop and slide in adjusted position.

9. The combination with a type-bar segment, of an adjustable stop mounted on said segment, an adjusting slide interposed between said stop and segment, said stop and slide having co-operating cam surfaces, and screws extending through openings provided in the stop and threaded into the segment to permit adjustment of the stop toward and from the face of the segment, but preventing lateral movement of the stop, said adjusting slide provided with elongated openings through which the screws extend to permit adjustment of the slide over the face of the segment to adjust the position of the stop, said screws serving to clamp the stop and slide in adjusted position.

10. The combination with a type-bar segment of a set of type-bars pivotally mounted thereon, the pivots of the type-bars arranged in an arc, the type-bars provided at 125 their free ends with types arranged to swing to a printing center, an arc-shaped stop concentric with said first-named arc and mounted on the segment between the type-bar pivots and the printing center, in position to 130

arrest the movement of the type-bars about their pivots as the types approach the printing point and permit the types to spring to printing position, a slide interposed between 5 the type-bar segment and said stop and arranged to slide over the face of the type-bar segment, said stop and slide formed with coöoperating cam faces to move the stop toward and from the segment as the slide is 10 moved, and thereby vary the point at which the type-bars are arrested, and means to lock the stop and slide in adjusted position.

11. The combination with pivotally mounted type-bars arranged to swing about their 15 pivots to a common printing center of a common stop member arranged to intercept the type-bars in their swinging movement as the type approach the printing point, said stop member adjustable in planes parallel to 20 itself to vary the stop in position for all of the type-bars, means for effecting such adjustment, a tapping projection on said

means, and means to lock the stop member in its adjustable position.

12. The combination with a support, of 25 type-bars mounted to swing in said support to a common printing center, a stop mounted on said support, and extending transversely of the type-bars in striking position for the latter as they approach the 30 printing point, an adjusting device interposed between the stop and its support, cam means on the stop, cam means on the adjusting support engaging the cam means on the stop, a tapping projection on said adjusting 35 means whereby the support may be adjusted always in planes parallel to itself, and means for holding said support in adjusted position.
